HANGER FOR SLIDING DOORS,
APPLICATION FILED SEPT. 7, 1918.

Patented May 27, 1919.

2 SHEETS-SHEET 2.

UNITED STATES PATENT OFFICE.

JOHN H. STEWART, OF NEW YORK, N. Y.

HANGER FOR SLIDING DOORS.

1,305,021.

Specification of Letters Patent. Patented May 27, 1919.

Application filed September 7, 1918. Serial No. 253,049.

To all whom it may concern:

Be it known that I, JOHN H. STEWART, a subject of the King of Great Britain, and a resident of the city of New York, Jamaica, 5 borough of Queens, in the county of Queens and State of New York, have invented a new and Improved Hanger for Sliding Doors, of which the following is a full, clear, and exact description.

10 This invention relates to a sliding door, and more particularly to a system of hanger links for slidably supporting the same.

The invention has for its general objects to improve and simplify the construction 15 and operation of devices for slidably hanging laterally sliding doors, the said device being of comparatively simple and inexpensive construction, reliable and efficient in use, and so designed as to permit a movable 20 door section to be supported on a fixed door section without the use of overhead supports.

A more specific object of the invention is the provision of a novel form of crossing 25 and pivotally connected links which are connected with the door sections in such manner as to be concealed between them in the open and closed position of the movable door section, the connections between the 30 links and door sections being such that the movable door section can be easily detached from the supporting door section.

With such and other objects in view, the invention comprises various novel features 35 of construction and arrangement of parts which will be set forth with particularity in the following description and claims appended hereto.

In the accompanying drawing, which 40 illustrates one embodiment of the invention and wherein similar characters of reference indicate corresponding parts in all the views,

Figure 1 is a front view of a door with 45 the movable door section in closed position, part of the operating means being in section;

Fig. 2 is a vertical section taken in the plane of the hanger when the sliding door 50 is in closed position;

Fig. 3 is a horizontal section on the line 4—4, Fig. 1;

Fig. 4 is a perspective view of the sliding door hanger;

Fig. 5 is a front view of one of the attaching plates; and

Fig. 6 is a detail sectional view on the line 7—7, Fig. 1.

Referring to the drawing, A designates a door or frame and B and B' are door sections, the first being laterally slidable and the second being fixed if desired. The stationary door section forms a support on which the movable door section is slidably mounted by means of a hanger which constitutes the subject matter of the present invention. The hanger C is constructed as shown in Fig. 4 and it comprises a pair of flat bars 1 and 2 which are movably connected at the center by a pivot 3, and these bars are so connected with the door sections that when the door is closed the bars will lie parallel with each other in side by side relation, and when the sliding door section is in open position the bars will cross each other in the form of the letter X. The bar 2 has its lower end pivotally fastened by a screw 4 or other securing means to the inner face of the sliding door at the inner lower corner there being preferably a plate 5 on said door, said plate having a socket 9 receiving the screw 4; and the upper end of the hanger bar 2 is provided with a headed pivot stud 6 which engages in the slot 7 of an attaching plate 8 set into the inner face of the fixed door section at the upper inner corner. The lower end of the bar 1 is provided with a headed pivot stud 10 that engages in a slot 11 in an attaching plate 12 fastened to the inner face of the fixed door section at the lower inner corner thereof. The upper end of the bar 1 has a headed pivot stud 14 which slides in a slot 15 in an attaching plate 16 secured to the inner face of the upper inner corner of the sliding door section. The slots of the attaching plates 8 and 16 have enlarged upper ends 18', giving said slots a key-hole form so that the headed pivot studs can be easily engaged with or disengaged from the door sections. The lower end of each hanger bar is formed with an offset lug 18 spaced apart from the end of the bar so as to provide a recess 19 into which the companion bar seats when the door sections are in closed position, as shown in Fig. 1, and it is to these lugs that the pivot studs 4 and 10 are connected, and by reason of the lugs the bars 1

and 2 can lie parallel one over the other in transverse alinement.

To insure against sagging the attaching plate 12 is formed with a shelf or ledge 31, 5 as shown in Fig. 3, so as to engage the bottom edge of the sliding door section and support the latter.

From the foregoing description taken in connection with the accompanying drawing, 10 the advantages of the construction and method of operation will be readily understood by those skilled in the art to which the invention appertains, and while I have described the principle of operation, together with the device which I now consider 15 to be the best embodiment thereof, I desire to have it understood that the device shown is merely illustrative and that such changes may be made when desired as fall within the 20 scope of the appended claims.

Having thus described my invention, I claim as new and desire to secure by Letters Patent:

1. The combination of a sliding door, a 25 supporting element, and a hanger for supporting the door on the said element, the hanger comprising a pair of bars pivotally connected at their centers and each bar hav-

ing one end pivotally connected with the sliding door and the other end pivotally 30 connected with the supporting element, each bar having one end formed with a returned member spaced from said bar to present a recess into which the other bar seats when the sliding door is in closed position, whereby the bars will lie parallel to each other 35 and in transverse alinement.

2. The combination of a sliding door, a supporting element adjacent thereto, a hanger for supporting the door on said element, said hanger comprising a pair of bars pivotally connected together at their centers, each bar having one end formed with an offset and turned-back lug to form a recess between the lug and bar, a pivot stud 40 extending outwardly from the lug to connect the lug of one bar with the sliding door and the lug of the other bar with the supporting element, said recesses being adapted 45 to accommodate the respective bars so that the latter will lie in transverse alinement, and means for connecting the opposite ends 50 of the bar with the sliding door and with the supporting element respectively.

JOHN H. STEWART.
